United States Patent Office

Des. 229,758
Patented Jan. 1, 1974

229,758

CHRISTMAS TREE BLANKET

Mary F. Bartel, 45 N. Hamilton St.,
Poughkeepsie, N.Y. 12601

Filed Feb. 14, 1972, Ser. No. 226,363

Term of patent 7 years

Int. Cl. D11—05

U.S. Cl. D29—1 B

FIG. I

FIG. 2

FIG. 1 is a top plan view of a Christmas tree blanket showing my new design; and

FIG. 2 is a top plan view of a modified form of a Christmas tree blanket showing my new design.

The blanket is of conventional thickness and the reverse side is plain and unornamented.

I claim:

The ornamental design for a Christmas tree blanket, as shown and described.

References Cited

UNITED STATES PATENTS

D. 84,573	7/1931	Drenthe	-----	D61—212
D. 188,192	6/1960	Riveras	-----	D29—1 B

OTHER REFERENCES

McCalls Needlework & Transfer Patterns, December 1956, p. 307, Snowman Skirt.

Better Homes & Gardens Christmas Ideas 1958, p. 99, Tree Skirts at top & lower right.

McCalls Novelty & Needlework Patterns, January-February 1959, p. 369, Christmas Trimming Motifs.

Notion & Novelty Review, September 1967, p. 37 Round Carpet left center.

JOEL STEARMAN, Primary Examiner

L. S. ZARFAS, Assistant Examiner